UNITED STATES PATENT OFFICE

162,016

COCKATEEL CAGE

Tilton E. Doolittle, Hamden, Conn., assignor to
 The Andrew B. Hendryx Company, New Haven,
 Conn., a corporation of Connecticut

Application July 14, 1950, Serial No. 11,174

Term of patent 14 years

(Cl. D31—2)

To all whom it may concern:

Be it known that I, Tilton E. Doolittle, a citizen of the United States, residing in Hamden, in the county of New Haven and State of Connecticut, have invented a new, original, and ornamental Design for a Cockateel Cage, of which the following is a specification, reference being had to the accompanying drawing, forming part thereof, in which

Fig. 1 is a front elevation of a cockateel cage, showing my new design;

Fig. 2 is a top plan view of the cage; and

Fig. 3 is an end elevation.

I claim:

The ornamental design for a cockateel cage, substantially as shown.

TILTON E. DOOLITTLE.
